ANDREW M. STEWART, OF TOLEDO, OHIO, ASSIGNEE TO THE NATIONAL SUPPLY COMPANY, OF TOLEDO, OHIO, A CORPORATION OF OHIO.

METHOD OF FORMING RIBBED METAL PIPES.

1,123,616.

Specification of Letters Patent.

Patented Jan. 5, 1915.

Application filed March 24, 1914. Serial No. 826,908.

To all whom it may concern:

Be it known that I, ANDREW M. STEWART, a citizen of the United States, residing at Toledo, in the county of Lucas and State of Ohio, have invented new and useful Improvements in Methods of Forming Ribbed Metal Pipes, of which the following is a specification.

My invention relates to the formation of longitudinal external ribs on metal pipes along the whole or a portion of the length of the pipes.

It is the object of my invention to produce from a metallic pipe a smaller pipe with external ribs extending longitudinally thereof, without appreciably, if at all, reducing the thickness of the pipe, the ribs being composed of portions of the pipe wall being doubled on themselves and pressed together. It is immaterial by what means my method is practiced. The ribs may be formed, for example, simply by hammering the sides of the tube, or in a press. I prefer to practice my method by the use of grooved rolls and have, therefore, illustrated the same in the accompanying drawings in which—

Figure 1 is a side elevation of a pair of rolls, subjecting a cylindrical pipe to the first step of my method; Fig. 2, a view of the left hand end of the pipe shown in Fig. 1; Fig. 3, an elevation of Fig. 1 looking at the latter toward the left; Fig. 4, a side elevation of a pair of rolls subjecting the pipe to a subsequent step of my method; and Fig. 5, an elevation of Fig. 3 looking at the latter toward the left.

On the drawings, Figs. 1 and 3, I show a pair of rolls 1 provided with registering peripheral grooves 2 which form a pass for the pipe 3 being treated therein. The rolls 1, as shown by arms on Fig. 1, rotate so as to cause the pipe 3 to travel toward the right. Fig. 2 shows the shape, in elevation, of the pipe 3 before being treated in the rolls 1. The width and depth of the grooves 2 are such as to flatten the pipe 3, to a more or less ellipsoidal cross-section, as shown on Fig. 3. The opposing rolls 1 preferably do not engage each other beyond the grooves 2 in order that the tube may bulge laterally beyond the grooves, as shown on Fig. 3.

After the pipe 3 has been reduced to the desired cross-section, which may be accomplished in one step or pass, or a series of

steps or passes by adjusting the rolls closer together after each pass, except the last, of the pipe through the rolls, in a manner well known to those acquainted with the art of rolling metal, it is passed through the rolls 5, Figs. 4 and 5. These rolls have their peripheral grooves 6 distinguished from the grooves 2 by being drawn with a shorter radius, which is shown to be the radius of the pipe at the conclusion of my method. The pipe may be brought from the generally elliptical shape shown on Fig. 3 to that of a longitudinally ribbed cylinder in one step or pass, or a series of steps or passes by adjusting the rolls 5 closer together between the roll passes in a manner well known. The shoulders 7 on the rolls, which are cylindrical portions of the rolls 5 extending beyond the grooves 6 and preferably parallel with the axis of the rolls, engage the sides or proximate portions of the pipe and double them upon themselves to form the ribs 8 extending lengthwise of the pipe.

I have shown only two pairs of rolls for changing a cylindrical pipe to a small pipe with external longitudinal ribs, but I may employ a number of pairs of rolls with grooves intermediate in size between the grooves 2 and 6 and reduce the pipe gradually in them from the original cylinder or equivalent shape to the final smaller ribbed cylinder. While I have illustrated and described only one of the ways in which my method may be practiced, and have shown and described rolls of definite shape, and have described my method as being practiced by definite steps, I regard my method as set forth in the appended claims, as independent of any definite mechanism or any definite number and character of steps. Indeed my method may be practiced by hand or power hammers or by a press, which is only a form of hammer.

It will be seen that the wall of the finished tube shown in Fig. 5 has the same thickness as the wall of the original pipe shown on Fig. 2, and as the wall in its intermediate stages of treatment as shown on Fig. 3. The ribs 8 are not composed of metal drawn or flowed from the body of the pipe into the space between the shoulders 7, but are composed of portions of the pipe pinched together, the ribs preferably having about twice the thickness that the tube wall has.

In the practice of my method I change a

substantially cylindrical pipe into a pipe with a shape or cross-section resembling an ellipse or oval, and simultaneously or afterward press together the longitudinal portions of the more or less elliptical or oval pipe at opposite sides of the major or longer axis to form longitudinal ribs on the pipe. Preferably at the same time I change the body of the pipe, that is the pipe irrespective of the ribs, back to a substantially cylindrical form by making the longer and shorter axes of the said shape equal. However, this step may be omitted if a cylindrical ribbed pipe is not desired as a finished article.

I claim—

1. The method of changing a substantially cylindrical pipe of substantially uniform wall-thickness into a longitudinally ribbed pipe having substantially the same wall thickness, which consists in changing the cross-section of the pipe by bending action without substantial flow of metal to a shape re-

sembling an ellipse, and pressing together the proximate portions thereof at opposite sides of the ends of the major axis of the said shape to form longitudinal ribs.

2. The method of changing a substantially cylindrical pipe of substantially uniform wall-thickness into a longitudinally ribbed pipe having substantially the same wall thickness, which consists first in compressing the tube by bending action without substantial flow of metal to form a cross-section having unequal axes, and then pressing together the proximate portions thereof at opposite sides of the ends of the longer axis to form longitudinal ribs and giving the body of the pipe a substantially cylindrical cross-section.

Signed at Toledo, Ohio, this 18th day of March, A. D. 1914.

A. M. STEWART.
